UNITED STATES PATENT OFFICE.

THADDEUS C. TUCKER, OF SAN FRANCISCO, CALIFORNIA, ASSIGNOR TO CALIFORNIA ALMOND GROWERS EXCHANGE, OF SAN FRANCISCO, CALIFORNIA, A CORPORATION OF CALIFORNIA.

ADVERTISING-DISPLAY.

1,400,190.

Specification of Letters Patent.

Patented Dec. 13, 1921.

Application filed August 31, 1920. Serial No. 407,197.

To all whom it may concern:

Be it known that I, THADDEUS C. TUCKER, a citizen of the United States, and a resident of the city and county of San Francisco, 5 State of California, have made a new invention—to wit, Improvements in Advertising-Displays; and I do hereby declare the following to be a full, clear, concise, and exact description of the same.

10 This invention relates particularly to advertising displays adapted to contain articles that it is desired to display, as well as advertise, and through the agency of a sign shaped in the form of a person and appropriately photo-lithographed to carry out the 15 representation conveying the impression that the intangible person portrayed on the sign is holding a container of visible articles.

An object of this invention is to provide 20 an advertising display in the form of a life like portrayal of a living object that can be efficiently and practically produced through the present advanced means by photo-lithography as a commercial substitute for attractive hand-colored displays.

A further object is to provide a collapsible container foldable according to the present well-known methods and provided with additional means thereon whereby advertising indicia may be detachably secured thereto. Other objects and advantages will appear as this description progresses.

In this specification and the annexed drawings, the invention is illustrated in the form 35 considered to be the best, but it is to be understood that the invention is not limited to such form, because it may be embodied in other forms, and it is also to be understood that in and by the claims following the 40 description it is desired to cover the invention in whatever form it may be embodied.

In the accompanying one-sheet of drawings,

45 Figure 1 represents an elevational view of a device constructed in accordance with my invention.

Fig. 2 represents a side elevation of the same.

Fig. 3 represents a plan view of the container blank and the means for holding the same in the assembled position.

Fig. 4 represents the plan view of the advertising sign blank.

In detail the construction illustrated in 55 the drawings, includes an advertising dis-

play medium generally designated by the numeral 1 and consisting of a sign member 2 and container portion 3 secured thereto in an appropriate manner. The display sign 2 and container 3 are preferably formed 60 from pliable cardboard, thin wood, metal or other desirable composition—the blank sheets of the desired material being stamped, cut or otherwise finished to the desired contour or profile. Thus the container 3 in the blank form is provided with the necessary slotted corners, creases and openings for folding the same into assembled position as a box-like container. The display sign 2 is likewise shaped into a contour representing 70 the silhouette of a photo-lithographic portrayal of a person printed thereon and is provided with suitable means whereby the same may be secured to the container 3 or quickly detached therefrom. Although it is 75 the object of my invention that the advertising sign 2 shall be provided with means adapted to engage predetermined openings provided in the container, I do not wish to confine myself solely to this fastening means 80 inasmuch as other appropriate devices could be made to subserve the same purpose.

By reference to Fig. 3, it will be noted that the container blank is substantially rectangular in form having the longitudinal 85 crease lines 5 and 6 and the lateral crease lines 7 and 8 passing transversely thereto, dividing the sheet into the front wall 9, rear wall 10 and the end members 11 and 12 respectively. The corner segments 13, 90 14, 15 and 16 are provided with appropriately shaped portions that are adapted to be inserted through the slotted openings provided in the side and end members of the container blank. The box is assembled into its 95 cubical form by bending the rear wall 10 into the vertical position relative to the base member 4, in which position the end members 11 and 12 respectively are raised so that the tabs 14 and 15 respectively on the 100 end members 11 and 12 engage suitable openings or slits 10' provided in the rear wall 10. The front section 9 is then bent upwardly and its engaging tabs 13 and 16 moved into engagement with the slits 12' 105 and 11' respectively provided in the end members 12 and 11, thus finishing the assembling of the box.

The rear sign member 2 is provided with cutout portions 20 and 21 adapted to be 110

positioned between the corner tab sections 14 and 15 and the outer face of the rear member 10, in which position the tab 22 extends downwardly on the outside of the 5 basket so as to be placed in substantially the same plane as the bottom 4.

It is desirable that the person portrayed on the display sign 2 have the arms of the body disposed so that one hand thereof will 10 overlap the upper edge of the rear wall 10 and by carefully slitting around the same, the finger portion thereof can be depressed in the form of a tab adapted to extend over the upper edge of the box 3 as if the same 15 were grasped thereby. To convey a more realistic meaning, the opposite hand is positioned on the display portion thereof so that a slot 23 provided substantially therethrough receives the handle member 24, de- 20 tachably mounted therein, with the opposite end thereof extending over the open face of the container in a graceful parabola with the end passing through slotted openings 25 provided in the front wall 9. Conveying 25 the effect that the person represented on the vertically positioned advertising sign, by means of the hand 26 overlying the rear wall of the container 10 and the hand 27 placed contiguous to the handle 24, is holding 30 the container 2 and offering the articles contained therein to an interested observer.

Although the figure of a small girl is represented on the advertising sign, it would be clearly within the purview of this invention to substitute some other person or object; to mount the same upon a container differently formed from the one shown and described or secure the same thereto in a different manner than that described and I 35

therefore do not want to limit myself specifically to the particular construction illustrated.

Having thus described this invention, what I claim and desire to secure by Letters Patent is:

1. An advertising display consisting of a sign with the contour thereof in the form of an animate object and appropriately decorated to represent the same; a container detachably secured to said sign; a handle on said container detachably secured to said sign in such a manner as to indicate it 45 grasped by the object represented thereon.

2. An advertising display consisting of a sign; a container formed of the same material as said sign, detachably secured thereto; and a handle thereon detachably secured to said sign.

3. An advertising display consisting of a sign; a collapsible container provided with 50 suitable fastening means for securing said sign thereto and supporting the same in the vertical position and a handle on said container detachably secured to said sign.

4. An advertising display consisting of a 55 sign; a container comprising a rectangular blank of material adapted to be appropriately creased and folded and detachably secured to said sign, and a handle adapted to be secured to an edge of said container and 60 to said sign.

In testimony whereof, I have hereunto set my hand at San Francisco, California, this 21st day of August, 1920.

THADDEUS C. TUCKER.

In presence of—

JOHN A. DIGOAN,
LINCOLN V. JOHNSON.
